UNITED STATES PATENT OFFICE

130,102

DESIGN FOR A TEXTILE FABRIC

Sidney Gaston, New Rochelle, N. Y.

Application September 26, 1941, Serial No. 103,518

Term of patent 3½ years

To all whom it may concern:

Be it known that Sidney Gaston, a citizen of the United States and resident of New Rochelle, in the county of Westchester, State of New York, has invented a new, original, and ornamental Design for a Textile Fabric, of which the following is a specification, reference being had to the accompanying drawing, forming part thereof, and in which the figure is a plan view of a piece of textile fabric showing my new design.

The area bounded by the dot, dash lines is a repeat of the design.

I claim:

The ornamental design for a textile fabric, substantially as shown and described.

SIDNEY GASTON.
